UNITED STATES PATENT OFFICE.

ELI CLAYBORNE, OF HOT SPRINGS, ARKANSAS.

SNOW-PLOW.

1,127,407.

Specification of Letters Patent.

Patented Feb. 9, 1915.

Application filed January 22, 1913. Serial No. 743,458.

To all whom it may concern:

Be it known that I, ELI CLAYBORNE, citizen of the United States, residing at Hot Springs, in the county of Garland and State of Arkansas, have invented certain new and useful Improvements in Snow-Plows, of which the following is a specification.

This invention relates to snow-plows.

The primary object of the invention is to provide a plow disposed to be attached to the pilot of a locomotive with means for melting or removing snow and ice.

A further object of the invention is to provide a construction of this character which may be conveniently transported and readily assembled on the pilot of the locomotive.

Another object of the invention is to provide a plow with a radiator for melting or removing snow, which will receive steam from the locomotive, the plow being of such design and dimensions as to completely shield the lower part of the locomotive.

A still further object of the invention is to provide a construction in which access to the radiator may be readily had when it is desired to properly drain and repair the same.

Another object of the invention is to provide a device which may be readily coupled to the pilot, the connection between the steam supply and the radiator being made after the device is coupled to the pilot.

In the drawings: Figure 1 is a side elevation showing the device arranged on the pilot of a locomotive; Fig. 2 is a top plan view; Fig. 3 is a section taken on the line 3—3 of Fig. 2; Fig. 4 is a rear elevation, the device being shown as supported upon trucks upon which it is moved when it is assembled on the pilot of the locomotive; Fig. 5 is a detail view of a portion of the radiator; Fig. 6 is a detail view of one of the shaft brackets which are disposed on the base of the plow and which receive the shafts of the trucks; Fig. 7 is a detail view of one of the attaching plates.

In the drawings, 10 designates the plow, the front shield or plate 11 of which tapers longitudinally to conform generally to the base outline of the pilot. This shield preferably comprises two plates 13 and 14 which are secured together at 15. The plates are concaved, and their meeting edges are cut circular to form the projecting points 16 and 17.

Secured to the rear wall of the shield adjacent its edges is a frame 18. This frame is connected at its upper end by the yoke 18', which extends transversely of the plow, 60 being bowed centrally to accommodate the pilot of the locomotive. This yoke is supported by truss rods or struts 18'' which are connected to the upright members of the frame, thus providing an effectual compact 65 supporting frame. This frame supports the radiator 19 which is formed in three sections, the end sections 20 and 21 and the intermediate section 22. The radiator comprises a series of tubes 23 which at their terminals 24 are connected with the curved conduits 25. These tubes 23 are supported intermediate their ends by upright curved beams 26, the terminals 27 and 28 of which are secured to the upper and lower beams 29 70 and 30 of the frame 18. The tubes are connected centrally by the couplings 31 which are curved to produce the desired configuration of the radiator, the supporting beams 26 being curved to conform to the concave 75 of the plates 13 and 14 of the shield.

The tubes 23' of the series are connected to pipes 33, the pipes being connected to couplings 32. These pipes 33, which are two in number, are disposed at both sides of the 80 coupling 34, the curved elbows or couplings 35 connecting the couplings 32 which receive the tubes 23''. It will thus be noted that the tubes are in communication and, at the same time, allow the necessary space for 85 the coupling 34. One of the upper pipes 23 is provided with a coupling 36. A flexible connection 37 is secured to this coupling, the terminal of said connection remote from the coupling being provided with the usual 90 air hose connection 38 whereby the same may be attached to a steam pipe 39 which is provided with a similar coupling 40. By this construction, it will be noted that steam may be supplied to the radiator, and that it 100 will circulate through the pipes 23 and the end connecting pipes 25, completely heating the shield and maintaining it at a temperature which will melt the ice and snow, which accumulates on the track.

A backing 41 of the same configuration as the shield incloses the radiator, said backing being preferably formed of asbestos or any other non-combustible material. A metallic backing 42 is secured to the asbestos backing, the metallic backing, as well as the asbestos backing, being secured to the frame 105 110

18. Thus, a chamber 43 is provided which concentrates the heat radiating from the tubes 23, thereby heating the plates which constitute the shield to an extent which causes the melting of the snow and ice with which the shield contacts. The lower set of tubes 23 are provided with drain cocks 44 by means of which the condensation water may be removed from the radiator. While 16 the particular form of radiator illustrated has been found effectual in practice, it will be understood that the construction may be changed to meet different conditions.

The lower beams 30 are provided with 15 bearings or bearing brackets 44 which consist of plates formed with the curved extensions 45, the curved extensions receiving the shafts 46 on which the wheels 47 are mounted. There are two pairs of bearings 44 disposed on the lower members 30 of the frame, the bearings of each pair of bearings being disposed at transversely opposite points on the frame in order that shafts may be arranged at the front and rear of the plow. 20 The trucks thus formed are used in moving the plow to a position where it may be attached to the pilot of a locomotive. The backing 42 is provided with loops 48 which, when the trucks are not in use, embrace the 25 shafts 46 adjacent the wheels which are supported thereon, thus carrying the trucks where they are readily accessible when it is desired to remove the plow from the locomotive.

30 The lower beams 30 of the plow frame 18 support a plurality of attaching plates 49, shown in detail in Fig. 7. These plates are formed with the offset portions 50 which embrace the beams 30 and the apertured extensions 51. The plates are four in number, there being two arranged at transversely opposite points adjacent the front of the plow and two arranged at transversely opposite points adjacent the rear of the plow. 40 The plates are disposed to be attached to the converging beams 52 of the pilot, there being a plurality of apertures formed in the plates in order that the proper adjustment may be made.

45 In assembling the plow on the pilot, the trucks are placed beneath the bearing brackets 44 and the device rolled until it contacts with the frame of the pilot. One side of the plow is then lifted until the plates 49 engage with the upper edges of the lower portion of the pilot frame, the openings in the plates being brought into register with the openings in the pilot frame, and bolts 53 passed through the aligned apertures. The other 55 side of the plow is then raised and the plates 49 of that side attached to the pilot. The plow is then forced toward the pilot, its front end being lifted until the coupling 34 is brought into locking engagement with a 60 corresponding coupling carried by the pilot. 65

The plow is then securely locked into position, being supported on the pilot and held against displacement by the coupling 35. The trucks are then removed and placed on the hangers 48 which are carried by the 70 backing 42 where they are supported until it is desired to remove the plow. After the plow has been attached to the pilot, the flexible connection 37 is connected with the steam supply pipe 39 and the radiator is 75 heated. It will be noted that in a comparatively short time the front plates of the plow will become heated to an extent which will cause them to melt the snow which accumulates on the track, the engine then being 80 allowed to pass through snow banks without danger of the snow or ice affecting the running gear.

The many advantages of a construction 85 of this character will be clearly apparent, as it will be noted that the device may be easily and economically manufactured and that it may be conveniently attached to locomotives such as are now in use without materially 90 altering their construction. 90

Having thus described my invention, what I claim as new and desire to secure by Letters Patent is:

1. A snow plow comprising a frame including converging side members, said side 95 members consisting of curved upright beams, horizontal beams connecting the terminals of said upright beams, a radiator including pipes supported by the upright beams, and plates secured to the inner and 100 outer faces of the beams.

2. A snow plow comprising a frame including converging side members, said side members including beams spaced one above 105 the other, and upright beams connecting the first beams, said upright beams being formed with openings, a series of pipes supported between the first beams at each side of the frame and projecting through the openings in the upright beams, and plates 110 secured to the inner and outer faces of the beams.

3. A snow plow comprising a frame including converging side members, said side 115 members consisting of beams arranged one above the other, upright beams connecting the first beams, said upright beams being formed with openings, a series of pipes supported between the first beams at each side of the frame and projecting through the 120 openings in the upright beams, the pipes at one side of the frame being connected to the pipes at the other side of the frame, and means for supplying steam to said pipes.

4. A snow plow for locomotives comprising a frame including converging side portions, each of which consists of beams arranged one above the other, upright beams connecting said first beams, a radiator housed between the first beams and sup- 125 130

ported by the upright beams, plates secured to the inner and outer faces of said beams, and angle bars supported in spaced relation on the lower of the first beams, said angle bars having inwardly directed portions disposed to be connected to the pilot of the locomotive.

5. A snow plow adapted for attachment to locomotives including a plow frame, plow 10 forming plates secured to the frame and to each other, a plurality of downwardly opening bearings carried by the lower portion of the frame, shafts adapted to seat in said bearings, and track engaging wheels carried 15 by the shafts.

6. A snow plow adapted for attachment to locomotives including a plow frame, plow forming plates secured to the frame and to each other, a plurality of downwardly opening bearings carried by the lower portion of the frame, shafts adapted to seat in said bearings, track engaging 20 wheels carried by the shafts, said shafts being detachable from the bearings, and means 25 carried by the frame for supporting the shafts and their wheels interiorly of the frame when they are removed from such bearings.

7. A snow plow including a plow body, supporting wheels detachably secured to the 30 body and capable of moving along a car track, means for detachably securing the plow body to the cowcatcher of a locomotive to rigidly support the body in place, and means for supporting the wheels clear 35 of the track when the plow body is so secured to the cowcatcher.

8. A snow plow including a plow body, a coupling head carried by the plow body for connection with the coupling head of 40 a locomotive, plates secured to the plow body and adapted for detachable connection with the cowcatcher of a locomotive, hooks carried by the plow body, shafts, truck wheels carried by the shafts, the shafts 45 being adapted to be supported by the hooks, and a plurality of open bearings carried by the plow body to detachably receive the shafts when the plow body is not attached to the locomotive. 50

In testimony whereof I affix my signature in presence of two witnesses.
